UNITED STATES PATENT OFFICE

155,292

DESIGN FOR A SLICING MACHINE

Cornelis Klingens, Barendrecht, Netherlands, and James Leslie Foster, La Porte, Ind., assignors to U. S. Slicing Machine Company, La Porte, Ind., a corporation of Indiana

Application May 14, 1947, Serial No. 139,034

Term of patent 14 years

(Cl. D55—1)

To all whom it may concern:

Be it known that we, Cornelis Klingens, a subject of the Queen of the Netherlands and a resident of Barendrecht, Holland, and James Leslie Foster, a citizen of the United States and a resident of La Porte, in the county of La Porte and State of Indiana, have invented a new, original, and ornamental Design for Slicing Machine, of which the following is a specification, reference being had to the accompanying drawings, forming a part thereof.

Fig. 1 is a perspective view showing the right side and far end of a slicing machine embodying our new design, with the carriage shown in a position nearly midway of its stroke;

Fig. 2 is a perspective view showing the right-hand side of the machine with the carriage at the end of its cutting stroke;

Fig. 3 is a perspective view showing the front and left-hand side of the machine; and

Fig. 4 is a perspective view showing the front of the machine.

We claim:

The ornamental design for a slicing machine, as shown.

CORNELIS KLINGENS.
JAMES LESLIE FOSTER.
